UNITED STATES PATENT OFFICE.

HENRY FALKE, OF BUFFALO, NEW YORK.

BAKER'S OVEN.

SPECIFICATION forming part of Letters Patent No. 255,264, dated March 21, 1882.

Application filed March 22, 1881. (No model.)

To all whom it may concern:

Be it known that I, HENRY FALKE, of the city of Buffalo, in the county of Erie and State of New York, have invented new and useful 5 Improvements in Bakers' Ovens, of which the following is a specification, reference being had to the accompanying drawings.

This invention relates more particularly to an apparatus for illuminating the interior of 10 bakers' ovens. Heretofore various kinds of illuminating apparatus have been placed either in the oven or in chambers or niches formed in the walls of the ovens; but they are liable to be extinguished or rendered inoperative or 15 impaired by the steam which is generated in baking, and some are very inconvenient in use.

The object of my invention is to produce an illuminating apparatus for bakers' ovens which is simple in construction, and reliable and convenient in use; and it consists of the construction and arrangement of the parts which compose my improved apparatus, and of the apparatus as a whole, as will be hereinafter fully set forth.

25 In the accompanying drawings, consisting of two sheets, Figure 1 is a longitudinal sectional elevation of the illuminating apparatus. Fig. 2 is a horizontal section in line x x , Fig. 1. Fig. 3 is an interior elevation of the apparatus. Fig. 4 is an exterior elevation thereof. Fig. 5 is a vertical section in line y y , Fig. 1, with the lamp removed. Fig. 6 is a perspective view of the lamp chimney.

Like letters of reference refer to like parts 35 in the several figures.

A represents a baker's oven of ordinary and well-known construction. A' represents the top arch, A^2 the front wall, and A^3 the floor, of the oven.

40 B represents a rectangular casing or chamber, of cast-iron or other suitable material, arranged in the front wall, A^2 , near the door of the oven, for the reception of the illuminating apparatus. The case B is open at its outer end and closed at its inner end by a plate, b , which is provided with an opening, b' , of suitable size to admit the light to the interior of the oven.

C is a sliding plate, arranged on the inner or 45 rear side of the plate b , to close or expose the opening b' at desire. The lower edge of the

plate C slides on a horizontal ledge or projection, c , formed on the plate b , and the contiguous edges of the plate C and ledge c are preferably beveled, so as to hold the plate C snugly 55 against the plate b .

d is a lug formed on the plate C near its lower edge and projecting forward through a horizontal slot, d' , in the plate b .

E is a hand-lever, pivoted at e to the bottom plate of the casing B , and connected with its inner end to the lug d , so that by operating the lever the sliding plate C can be adjusted to cover or expose the opening b' . The plate b and ledge c extend laterally on the inner side 65 of the front wall of the oven to form a bearing or support for the sliding plate C when it is adjusted to expose the opening.

F represents a shield or projecting plate, arranged on the inner side of the sliding plate 70 C , to prevent ashes and cinders from falling into the depression in which the plate C works. The shield F projects above the floor of the oven and terminates below the lower edge of the opening b' , so as not to interfere with the 75 admission of light to the interior of the oven. The shield F is secured to the oven by screws f . The upper edge of the plate C is guided by a horizontal bar, G , secured to the plate b by screws g .

H represents the supporting-table, on which the lamp I is placed. The table H is provided with legs h , whereby sufficient space is formed between the platform of the table and the bottom plate of the casing B to permit the free 85 movement of the lever E .

K is a vertical plate, secured to the inner end of the table H , and provided with an opening, k , which coincides with the opening b' in the plate b . The opening k is covered by a sheet 90 of mica, k' , which is held in place by a frame, k^2 , or by any other suitable means. The flame of the lamp I is arranged at a height to properly illuminate the interior of the oven through the openings b' and k . The table H is readily 95 removed from the casing B when it becomes necessary to clean or renew the mica k' , or for other purposes.

L is a flue, formed in the front wall, A^2 , of the oven, for carrying off the products of combustion which rise from the lamp. The inner end 100 of the flue L connects with an opening, l , in

the top plate of the case B over the flame of the lamp, and the outer end of the flue opens in front of the wall A², as clearly shown.

M represents air-flues formed in the front 5 wall, A², on each side of the casing B for the purpose of preventing the overheating of the same.

m is an air-inlet flue arranged under the bottom plate of the casing B and connecting with 10 the lower ends of the flues M, and m' is an air-outlet flue arranged over the top plate of the casing B and connecting with the upper ends of the flues M. The exterior air enters through the inlet m, passes upward through the flues M, 15 where it becomes heated, and escapes through the outlet m'. In this manner the casing B is constantly surrounded by cool air-currents, which carry off the heat which the casing absorbs from the surrounding hot brick walls. 20 The top plate of the casing B may be provided with holes m², to facilitate the escape of the hot air from the casing B. The air-escape flue m' and the flue L may be connected, either or both, with a chimney or other air-conduit, 25 if it should be necessary to increase the draft through these passages.

N represents the oil-reservoir of the lamp I; and n n are two longitudinal ribs secured to 30 the bottom of the oil-reservoir, whereby the latter is supported above the table H, so as to form an air-passage between the bottom of the oil-reservoir and the table H, whereby the oil-reservoir is kept cool.

O represents the lamp-chimney, composed of 35 two metallic side plates, p p, and two mica plates, p', which latter are arranged in line with the openings b' k. The mica plates p' are held under overlapping flanges q, formed with the side plates, p, a similar flange, q', formed 40 on the bottom plate, p², and a similar flange, q², formed on a metallic plate, p³, which connects the side plates, p, above each mica plate. The flange q² is made so large that after the sheet of mica is introduced under the side 45 flanges, q, it can be pushed under the upper flange, q², until it is raised over the lower flange, q', when, by pushing the sheet of mica down behind the lower flange, q', it is secured in place.

50 R is a reflector, arranged in line with the flame, and arranged to throw the light into the oven through the opening b'. When a large quantity of steam is generated in the oven by injecting water into the same, or otherwise, the 55 slide C is closed to protect the mica k' from the effects of the steam, whereby the mica is kept clean. When the oven-door is opened for in-

roducing or removing the articles to be baked the slide C is opened by a simple movement of the lever E, thereby throwing the full light of 60 the lamp into the oven and enabling the baker to manipulate the articles in the oven with convenience.

The sheet of mica, k', which covers the opening b', prevents the steam in the oven, when 65 the slide C is drawn, from blowing out the lamp. If there is a pressure of steam in the oven, it is relieved as soon as the slide C is opened by the steam escaping through the slot d', in which the lug d works. The air-passages 70 around and through the casing prevent the overheating of the casing and the lamp placed in the same, and permit a kerosene-lamp to be used with perfect safety.

It is obvious that a gas-flame may be used 75 for illuminating the oven; but I prefer the use of an oil-lamp, as I find it to afford a steadier and brighter light.

I claim as my invention—

1. The combination, with an oven, A, of the 80 chamber B, provided with an opening, b', a slide, C, and a shield, F, protecting the slide C, substantially as set forth.

2. The combination, with an oven, A, of a chamber, B, provided with an opening, b', and 85 a removable table, H, provided with a vertical plate, K, having an opening, k, coinciding with the opening b' and covered by a sheet of mica, k', substantially as set forth.

3. The combination, with an oven, A, of a 90 chamber, B, provided with an opening, b', and adapted to receive an illuminating apparatus, and air-conduits M m m', surrounding the chamber B, whereby the latter is cooled, substantially as set forth.

4. The combination, with an oven, A, of a chamber, B, provided with an opening, b', and 95 a lamp, I, having its oil-reservoir provided on its under side with longitudinal ribs n, whereby an air-space is formed between the bottom 100 of the oil-reservoir and the bottom plate of the chamber B and the oil-reservoir is kept cool, substantially as set forth.

5. The combination, with an oven, A, of a chamber, B, provided with an opening, b', and 105 a lamp, I, having a chimney, O, composed of metallic side plates, p p, and mica plates p', arranged in line with the opening b', substantially as set forth.

HENRY FALKE.
